UNITED STATES PATENT OFFICE.

FREDOLF J. PETERSON, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

CARD-HOLDER.

1,374,863.

Specification of Letters Patent. Patented Apr. 12, 1921.

Application filed September 10, 1917. Serial No. 190,496.

To all whom it may concern:

Be it known that I, FREDOLF J. PETERSON, a citizen of the United States, residing at Alliance, in the county of Stark and State of 5 Ohio, have invented new and useful Improvements in Card-Holders, of which the following is a specification.

The invention relates to a rack or frame for holding a large number of cards, and 10 especially to hold the same in such a manner as will conceal one portion and disclose another portion of the face of each card; and the object of the improvement is to provide, by a simple construction, such a frame as 15 will hold and display a maximum number of cards within a minimum amount of space.

This general object and ancillary advantages are attained by nesting a series of 20 slightly spaced V-shaped sheets or plates of stiff material, so that cards may be entered on both sides of the series between the free edge of one sheet and the adjacent face of the next sheet.

25 A preferred embodiment of the invention as used in an ice cream manufacturing business, is illustrated in the accompanying drawings forming part hereof, in which—

Figure 1 is a perspective view of several 30 frames constructed in accordance with the present invention, one of which frames is partly broken away to show details;

Fig. 2, a fragmentary cross section as on line 2—2, Fig. 3 showing details of construction;

Fig. 3, a longitudinal section as on line 3—3, Fig. 2, showing other details of construction;

Fig. 4, a detached perspective view partly 40 broken away, of one of the V-shaped plates; and

Fig. 5, a perspective view of a tag having a detachable coupon for filing in the card holder.

45 Similar numerals refer to similar parts throughout the drawings.

A plurality of rectangular frames are preferably pivoted at one side or edge to a supporting bracket 1, so that the frames can 50 be swung, opened and closed like the leaves of a book, for giving access to both sides of each frame; and the sides and ends of the frames may be made of the flat rim strips 2 and 2', and a plurality of flat partition strips 3, may be longitudinally secured at

spaced intervals between the end strips 2' of the frame, for making a plurality of compartments therein.

In each longitudinal space or compartment thus formed, is mounted a series of V-shaped sheets 4 made of metal or other stiff material, each sheet being nested in another, but being located at a spaced interval therefrom, as shown more clearly in Fig. 2. The V-shaped sheets 4 may be mounted in the 60 frame by stamping or striking an eye or loop 5 inward from the angle adjacent to each end of the sheet, as best shown in Fig. 4, through which loops a wire or rod 6 is passed for supporting the V-sheet in proper 65 position. The supporting wires or rods 6 may be passed through apertures 7 in the partition and side strips of the frame, and finishing plates 8 may be secured to the side strips for concealing the ends of the 70 wires and retaining them in the frame.

By this construction and arrangement, the receptacle formed by each V-sheet of each 75 series is individually supported in nested arrangement with reference to the adjacent 80 sheets, and although each sheet may rotate a slight distance upon the pivotal support formed by the supporting wire, it is nevertheless maintained in upright or operative 85 position by the contiguity of the next adjacent sheet which is nested within it. At the same time, the several sheets are sufficiently spaced apart to permit the entrance of one or more cards in each side between the free edges of one sheet and the adjoining 90 faces of the next-above adjacent sheet; and when so inserted the angle of the sheet or the supporting wire, as the case may be, furnishes a stop for the lower edges of the 95 cards.

The card holder thus described, may be used for holding cards constituting a directory of the guests of a hotel or for any other like purpose requiring the filing of a large number of cards within a limited 100 space; and as shown, the appliance is well adapted for holding the coupons 9 which may be detached along the weakened line 10 from the body of the tag 11 which may be used for marking the cans or buckets sent 105 out by an ice cream manufacturer.

In such a business, a large number of cans or buckets are sent out daily to customers at distant points and unless returned within a limited time, soon become forgotten and 110

lost; and for this reason there is usually a regulation requiring the return of such cans or buckets within a certain number of days from the time of delivery.

5 To check up the location of outstanding cans, the date of shipment and time for return is preferably noted at the top of the tag carrying the name and address of the customer, and likewise at the top of the coupon originally connected therewith; and at the time of shipment, the coupon is detached 10 from the tag and inserted in the card holder, which may have its retaining plates provided with an exposed number 12 corresponding to the number of the particular 15 customer.

When filed in the card holder, the date of shipment and time for return visibly protrudes above the retaining sheet, and it is 20 evident that by these means the outstanding

cans or buckets can be readily checked at any time, by a mere inspection of the card holder, and that upon a return thereof, the corresponding coupons may be removed from the holder.

25

I claim:

1. A card holder including a series of V-shaped receptacles spaced apart in nested arrangement, and means supporting the receptacles at their angles only permitting 30 them to rock laterally with reference to each other on their respective supports.

2. A card holder including upright partition strips and transverse wire supports, and a series of nested V-shaped receptacles 35 pivotally supported at their angles upon the wires for lateral movement with reference to each other.

FREDOLF J. PETERSON.
